CLAIM

The ornamental design for a lighting fixture, as shown and described.

DESCRIPTION

FIG. 1 is a perspective view showing a new design for a lighting fixture angled rearward approximately 15 degrees from vertical;
FIG. 2 is a front view of the lighting fixture of FIG. 1;
FIG. 3 is a bottom view of the lighting fixture of FIG. 1;
FIG. 4 is a perspective view of the lighting fixture of FIG. 1 angled rearward approximately 30 degrees from vertical;
FIG. 5 is a perspective view of the lighting fixture of FIG. 1 angled rearward approximately 45 degrees from vertical;
FIG. 6 is a perspective view showing a second embodiment of a new design for a lighting fixture angled rearward approximately 15 degrees from vertical;
FIG. 7 is front view of the lighting fixture of FIG. 6;
FIG. 8 is a bottom view of the lighting fixture of FIG. 6;
FIG. 9 is a perspective view of the lighting fixture of FIG. 6 angled rearward approximately 30 degrees from vertical;
FIG. 10 is a perspective view of the lighting fixture of FIG. 6 angled rearward approximately 45 degrees from vertical;
FIG. 11 is a perspective view showing a third embodiment of a new design for a lighting fixture angled rearward approximately 15 degrees from vertical;
FIG. 12 is front view of the lighting fixture of FIG. 11;
FIG. 13 is a bottom view of the lighting fixture of FIG. 11;
FIG. 14 is a perspective view of the lighting fixture of FIG. 11 angled rearward approximately 30 degrees from vertical;

FIG. 15 is a perspective view of the lighting fixture of FIG. 11 angled rearward approximately 45 degrees from vertical;
FIG. 16 is a perspective view showing a fourth embodiment of a new design for a lighting fixture angled rearward approximately 15 degrees from vertical;
FIG. 17 is front view of the lighting fixture of FIG. 16;
FIG. 18 is a bottom view of the lighting fixture of FIG. 16;
FIG. 19 is a perspective view of the lighting fixture of FIG. 16 angled rearward approximately 30 degrees from vertical;
FIG. 20 is a perspective view of the lighting fixture of FIG. 16 angled rearward approximately 45 degrees from vertical;
FIG. 21 is a perspective view showing a fifth embodiment of a new design for a lighting fixture angled rearward approximately 15 degrees from vertical;
FIG. 22 is front view of the lighting fixture of FIG. 21;
FIG. 23 is a bottom view of the lighting fixture of FIG. 21;
FIG. 24 is a perspective view of the lighting fixture of FIG. 21 angled rearward approximately 30 degrees from vertical;
FIG. 25 is a perspective view of the lighting fixture of FIG. 21 angled rearward approximately 45 degrees from vertical;
FIG. 26 is a perspective view showing a sixth embodiment of a new design for a lighting fixture angled rearward approximately 15 degrees from vertical;
FIG. 27 is front view of the lighting fixture of FIG. 26;
FIG. 28 is a bottom view of the lighting fixture of FIG. 26;
FIG. 29 is a perspective view of the lighting fixture of FIG. 26 angled rearward approximately 30 degrees from vertical; and,
FIG. 30 is a perspective view of the lighting fixture of FIG. 26 angled rearward approximately 45 degrees from vertical.
The broken lines showing portions of the lighting fixture are included for the purpose of illustrating environment and form no part of the claimed design.
